FOLDING BERTH

Albert A. Hopeman, Jr., and John A. Bohnsack,
Waynesboro, Va., assignors to Hopeman Bros.,
Inc., New York, N. Y., a corporation of Delaware

Application December 28, 1945, Serial No. 637,594

2 Claims. (Cl. 5—9)

1

This invention relates to folding berths and, more particularly, to those of the variety mounted to swing between a substantially vertical closed position against its supporting partition or wall and a horizontal open position for use, such as employed in restricted spaces of ship staterooms and railway sleeping cars. One object of the present invention is to provide an improved berth of the above variety and particularly one having a more simple, rugged, and conveniently operated construction.

Another object is to supply a berth of the above type adapted, when not in use, to be swung into a recess in a bulkhead or partition wall and having simple and effective mounting means located mainly on and within the bulkhead or partition wall, without encumbering the berth itself.

A further object is to provide a berth having mounting means constructed as described and so arranged that the berth occupies minimum room space in both open and closed positions.

Still a further object is to provide a berth folding into a recess in a wall or bulkhead and so mounted that in open or lowered position it projects to a minimum distance from the recess into the room space while, in raised or closed position, it closely fits the recess so as to continuously close and neatly fill the same.

To these and other ends the invention resides in certain improvements and combinations of parts, all as will be hereinafter more fully described, the novel features being pointed out in the claims at the end of the specification.

In the drawings:

Fig. 1 is a side elevation partly in section of upper and lower folding berths embodying the invention;

Fig. 2 is an enlarged, sectional elevation with the berth in raised or closed position as seen from the line 2a—2a in Fig. 3;

Fig. 3 is a sectional elevation on the line 3a—3a in Fig. 5, showing the berth closed;

Fig. 4 is a similar view showing the berth open;

Fig. 5 is a sectional elevation on the line 5a—5a in Fig. 4, and

Fig. 6 is a sectional plan view on the line 6a—6a in Fig. 5.

The embodiment of the invention, herein disclosed by way of illustration, comprises, preferably, a room space having at one side thereof a vertical bulkhead or partition 10, a deck or floor 11, and a deck or ceiling 12. Partition 10 is formed, by any suitable type of construction, with inwardly extending wall portions 13 forming sub-

2

stantially rectangular upper and lower berth receiving wells or recesses indicated generally at 14 and 15. The partition walls in the present instance are of sheet metal construction, as shown, and the bottoms of the recesses are provided at their forward or open sides with low flanges 16 and 17, for a purpose hereafter described. As the upper and lower berths have substantially the same construction, the description of one will be understood to apply to both, except as pointed out.

Each berth pan, indicated generally at 18, is preferably formed with a rigid metal bottom 19 (Fig. 3) having stiffening lengthwise corrugations as shown, with a smooth plate 20 on one side thereof which forms a smooth wall neatly closing the berth recess, when the berth is in closed position. The pan comprises side walls 21, a front wall 22 and a rear wall 23 for holding the mattress 24. A pair of generally triangular brackets 25 are secured in the rear end corners of the pan bottom 19, being formed for this purpose with inwardly turned flanges 26 secured, as by means of screws or bolts 27, to the bottom of the pan. Flanges 26 are preferably extended up the rear side of brackets 25 to provide triangular stiffening flanges 28 which are fastened, as by means of screws 29, to the back wall 23 of the pan. Brackets 25 are preferably formed as steel forgings or castings and afford rigid means for supporting the pan on the partition.

The means for mounting each pan for swinging movement comprises, preferably, a pair of brace or link bars 30, one pivoted on the inner surface 35 of each pan bracket 25, as by means of a pivot stud 31 fixed in the bracket in spaced relation with the rear side of the pan. Each link is pivoted at its upper end to the corresponding side wall of the recess as at 32. Each link 30 is somewhat 40 offset laterally as at 33, so as to locate its ends in properly spaced relation with the pan bracket and recessed wall, respectively. These links provide one of two pivotal means of support at each 45 end of the pan and their extreme outward position of movement during the swinging of the pan is shown by the dotted line position indicated at 34, Fig. 4.

The other pivotal support for each end of each pan preferably comprises a guide block 37 of 50 generally rectangular shape having trunnions 38 and 39 projecting from opposite sides thereof. Trunnion 38 is pivotally received in an opening formed in the corresponding bracket 25 in such position so as to lie adjacent the rear edge of the pan as shown. The other trunnion 39 is pivotally

and slidably received in a vertically extending guide opening or slot 40 cut in a wall section or plate 41 forming part of the adjacent side wall of the recess, the plate 41 being detachably secured to the recess wall as by means of screws 42. Trunnion 39 projects beyond the side of plate 41 opposite the recess and pan and has fixed thereto an angular bracket 43. Bracket 43 has an opening therein for slidably receiving a guide rod 44 extending vertically parallel with the plate 41 and its slot 40, the rod having its upper end inserted through an opening in an upper bracket 45 fixed on the plate, with a pin 46 passed through the rod to suspend it from the bracket. Coiled about and guided on the rod is a compression spring 47 bearing at its upper end against bracket 45 and at its lower end against bracket 43 on the guide block, so as to maintain downward pressure on the latter and on trunnion 38 tending to swing the pan upwardly on trunnion 38 and link 30 as supports and thus counterbalance the weight of the pan and mattress.

The floating pivot and counterbalance means comprising the trunnion blocks 37 and springs 47 are assembled in operating position before the berth pan is bolted to the triangular brackets or gussets 25. The spring is compressed by forcibly moving the parts to the position shown in Fig. 4 and when the parts reach such tensioned position, a short bolt is screwed through threaded openings 35 and 36 on each link 30 and bracket 25 so as to temporarily hold the parts in such relation. The berth pan is then bolted to the brackets, after which the bolts are removed to release the mechanism for its intended operation.

The ends of slots 40 in the wall plates 41 serve as stops for limiting the movements of trunnions 39 and precisely locating the berth pan in open and closed positions, and by suitably locating these slots and the points of pivotal attachment of the links 30, the height of the pan above the deck or floor in lowered position may be selectively determined along with determination of the height of the berth recess and its bottom wall and flange 16 or 17 which serves to cover the space in the bottom of the recess. In raised or closed position the smooth bottom wall 20 of the pan neatly fills and closes the open front side of the berth receiving recess, as shown in Fig. 3. The guide blocks 37 serve to space and center the pan in its receiving recess. The berth may be latched in its upper or closed position by any known or suitable latch means indicated generally at 20a, such, for example, as the latch means commonly employed on the upper berth of Pullman railway cars and forming no part of the present invention.

While the pivotal supports afforded by the links 30 and sliding trunnions 31 are amply strong to sustain the full weight of the berth and its occupant, additional support may be provided, if desired, by attaching to each outer corner of the lower pan pivoted supporting struts or legs 48, these legs being adapted to swing parallel with the pan in its folded position, or made detachable, as desired. Similarly, a strap 49 may be detachably pivoted to a post 50 depending from the deck or ceiling 12 over each outer corner of the berth, the lower end of the strap being connected as at 51 to the pan, either detachably or so as to fold parallel with it in its closed position, as desired.

It is evident from the above construction that the pan and berth may be swung from one position to another by the application of a light force, the berth being maintained by the sliding pivot

block with its rear edge in close proximity to the black wall of the recess, so that the berth, in raised and lowered positions and in movements therebetween, projects a minimum distance into the room space. This pivotal control is accomplished, furthermore, by means located on the detachable plates 41 forming part of the walls of the berth receiving recess, the links 30 and guide blocks 37 occupying but little space within the recess. The berth pan is thus advantageously left unobstructed for occupation by the mattress substantially free of encumbrance by mounting mechanism.

It will be evident that if the berth were swung about fixed pivots in place of the trunnions of the sliding or floating pivot block 37, it would be necessary, in order to afford clearance in open position, to lower the bottom of the wall recess to a considerable distance below the bottom of the berth in closed position, thus leaving a substantial and unsightly gap in the wall below the berth. The mounting of the berth on sliding or floating pivots as described, thus serves to both minimize the projection of the berth into the room space in lowered position and enable it to closely fit and close the wall recess when the berth is moved to closed position, thus maintaining for the wall a continuous, smooth and neat appearance. The mechanism, as a whole, is extremely simple, rugged and inexpensive in character, easy to install, and convenient in use.

It will thus be seen that the invention accomplishes its objects and while it has been herein disclosed by reference to the details of preferred embodiments, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

We claim:

1. A folding berth movable between raised and lowered positions comprising a supporting partition 45 against which said berth is folded in raised position, said partition having a vertical guide slot therein, a berth pan, link means pivotally connected with said partition and pan and supporting said pan for folding movement on said partition, a guide block movable in said slot having on one side of said partition a pivotal connection with said pan and provided on the other side of said partition with a bracket, a guide rod on said partition, and a coiled spring on said rod having one end bearing on said bracket in a direction tending to lower said guide block and raise said pan.

2. A folding berth structure comprising a supporting wall formed to provide a berth receiving recess therein, a berth pan, links pivoted to said wall and to said pan at points spaced inwardly from one side thereof, guide means mounted for movement in vertical guide openings in said wall and connected with said pan adjacent said side thereof, spaced brackets on said guide means and on the sides of said wall opposite said pan, respectively, guide rods mounted in said brackets, and compression springs coiled about said rods between said brackets and tending to move said guide means vertically in said openings and swing said pan to closed position in said recess.
